UNITED STATES PATENT OFFICE.

ARCHIE D. COALSON, OF BIRMINGHAM, ALABAMA.

FROG.

1,252,400.

Specification of Letters Patent.

Patented Jan. 8, 1918.

Application filed April 17, 1916. Serial No. 91,705.

To all whom it may concern:

Be it known that I, ARCHIE D. COALSON, a citizen of the United States, residing at Birmingham, in the county of Jefferson and State of Alabama, have invented a new and useful Frog, of which the following is a specification.

This invention relates to railroad frogs, one object being to provide a removable point which, when worn, can be replaced by a new one, thereby avoiding the expensive renewal of the entire frog which has heretofore been necessary when the point has become worn.

15 A further object is to provide simple and efficient means for holding the point firmly in position so that there is no danger of its working loose.

With the foregoing and other objects in view which will appear as the description proceeds, the invention resides in the combination and arrangement of parts and in the details of construction hereinafter described and claimed, it being understood 25 that changes in the precise embodiment of the invention herein disclosed, can be made within the scope of what is claimed, without departing from the spirit of the invention.

In the accompanying drawings the preferred form of the invention has been shown.

In said drawings:

Figure 1 is a plan view of a frog embodying the present improvements, portions of rails being shown connected thereto.

35 Fig. 2 is a central longitudinal section through the frog.

Fig. 3 is an enlarged section on line A—B Fig. 1.

Fig. 4 is an enlarged section on line C—D Fig. 1.

Fig. 5 is an enlarged section on line E—F Fig. 1.

Fig. 6 is an enlarged section on line G—H Fig. 1.

45 Fig. 7 is a plan view of the removable point.

Referring to the figures by characters of reference, 1 and 2 designate diverging wing rails and diverging from the inner ends of these wing rails are flanges 3 and 4. A substantially horizontal web 5 is interposed between and formed integral with the wing rails and the flanges and forms the bottom of the channel provided between the wing rails and flanges for the reception of the flanges of the car wheels. That portion of

the web between the flanges 3 and 4 is formed with a triangular depression 6 extending from the end of the web to a point close to the inner ends of the flanges 3 and 4. The bottom of this depression may be formed with openings 7 and the walls of the depression are preferably provided with longitudinal grooves 8 overhung by the adjacent upper portions of the web 5. The opposed grooves 8 are designed to receive flanges 9 extending along the sides of a wedge-shaped point 10 which, when thrust longitudinally within the depression 6 will fit snugly therein with its apex projecting 70 upwardly from the apex of the depression. The base of the point rests on the bottom of the depression 6 as shown particularly in Fig. 4 and the top of the point is obviously disposed in the same plane as the tops of 75 the wing rails 1 and 2 and the flanges 3 and 4. That portion of the point located beyond the web 5 is shaped to lie flush with the bottom of the remaining portion of the frog. This projecting portion of the point has base 80 flanges 11 which may be secured to a cross tie by spikes in the usual manner. A tongue 12 is extended from the end of the frog point, and the sides of this tongue are parallel with the sides of the point. Longitudinal grooves 13 are formed along the upper edges of the sides of the tongue 12 and are so shaped as to receive the inner sides of the heads of rails 14, the ends of these rails abutting against shoulders 15 at the sides 90 of the tongue 12 so that when the rails are arranged against the sides of the tongue their heads will constitute continuations of the top of the point. The rails are fastened to the tongue by means of bolts 16 extending transversely through the webs of the rails and through the tongue 12.

Base flanges 17 extend outwardly from the wing rails 1 and 2 and from the flanges 3 and 4 and also extend across the outer ends of the flanges 3 and 4 and up to the sides of the point 10. The inner sides of the wing rails 1 and 2 are cut away longitudinally as at 18 to receive the outer sides of the heads of rails 19. These rails are fastened to the wing rails by means of bolts 20 in the usual manner. Base flanges 21 are preferably provided along the inner sides of the wing rails and at the adjacent end of the web 5 and are adapted to aline with the 110 corresponding base flanges of the rails 19.

Obviously when the point 10 becomes

worn it can be removed simply by detaching rails 14 from the tongue 12 and then withdrawing the point longitudinally from the depression 6.

- 5 The rails 14 are to be provided with fish plates 22 which lap and are secured to the sides of the point 10, recesses 23 being provided in the sides of the point for the reception of the fish plates and there being bolt 10 receiving openings 24 extending transversely through the point.

What is claimed is:—

A frog including oppositely diverging wing rails and flanges, an integral web connecting the same and having a V-shaped

depression between the flanges, there being longitudinal grooves in the walls of the depression, and a point insertible longitudinally into the depression, flanges on the point adapted to enter the grooves, and flanges on 20 the point adapted to seat on and for attachment to the ties.

In testimony that I claim the foregoing as my own, I have hereto affixed my signature in the presence of two witnesses.

ARCHIE D. COALSON.
